UNITED STATES PATENT OFFICE.

THOMAS J. BOWEN, OF WILMINGTON, DELAWARE; MARY E. BOWEN ADMINISTRATRIX
OF SAID THOMAS J. BOWEN, DECEASED.

MACHINE FOR BROADCASTING A WIDE AREA OF ILLUMINATION.

Application filed March 9, 1928. Serial No. 260,477.

The present invention relates to an improved apparatus for broadcasting illumination over a substantial area, the primary purpose being to perform this function in a practical and economical manner, without any flickering shadows.

The time has arrived where it is essential to illuminate extremely wide areas, such as around freight yards, on the sea from light 10 houses and all such similar places, and more especially to illuminate aviation landing fields, the last need being most essential.

To carry out these needs, that is to say to illuminate such places, it is the purpose to 15 provide tall towers, and to mount thereon the present improved device for creating a true sphere of illumination, such as may spread spherically over a substantial wide area.

Another purpose is to provide a round ring 20 frame of substantial diameter disposed in a perpendicular plane and revoluble on a vertical axis and provided with a plurality of search lamps having substantial candle power, the lamps extending about the convexed surfaces of the round frame, whereby upon driving 25 the frame at a substantial rate of speed on its vertical axis the lamps will disperse a true sphere of illumination, it being the purpose to drive the round ring frame at a substantial rate of speed so as to avoid flickering 30 shadows.

It is possible, as illustrated, to provide intersecting round ring frames, each intersecting round ring frame having high power 35 search lamps, thereby creating an extreme spherical illumination over a very wide area, insuring against any flickering shadows, and at the same time permitting the driving means for the frames to operate much slower than when operating a single round ring frame.

It may also be essential to note that certain of the high candle power lamps may have colored lenses, it being possible to use conventional type of make and break circuit closures, for turning the lamps on and off, for signaling purposes. This apparatus may be used for any purposes in addition to those above mentioned.

It is to be understood that the particulars herein given are in no way limitative, and that while still keeping within the scope of the invention, any desired modification of details and proportions may be made in the construction of appliance according to circumstances.

The invention comprises further features and combination of parts to be hereinafter set forth, shown in the drawings and claimed.

In the drawings:

Figure 1 is a view in elevation of the improved machine for broadcasting illumination constructed in accordance with the invention.

Figure 2 is a plan view of the same.

Figure 3 is a vertical sectional view.

Figure 4 is a view in elevation of a modified construction wherein there are two round ring frames shown.

Figure 5 is a plan view of Figure 4.

Figure 6 is a detailed view of the support 70 and the tracks 14 showing the cooperative parts thereof.

Figure 7 is a sectional view through the Figure 6, also showing the tracks 14, the support 13 and the brushes 12.

Referring to the drawings: 1 identifies a base, and rising therefrom is a tower 2 which may be any height and may be of any suitable construction, such as angle iron frame work. This tower may be on the plan of the well known Eiffel tower though not necessarily, but should be of sufficient height to enable the lamps to disperse a substantial wide globular illumination, widely reaching over the surface of the ground or sea.

Mounted in bearings of the tower is a vertical shaft 3, having its lower end operatively connected by gears 4 to a motor 5, of sufficient horse power to enable the round ring frame 6 (which is mounted at the upper end of the shaft) to revolve rapidly, sufficiently to enable the high candle powered search lamps to disperse rays of light, and due to the rapid rotation of the round ring frame the rays of light dispersed will be in true spherical contour and without flickering shadows.

The high candle power search lamps may be of the usual type, embodied in the round ring frame and due to the convexed surface of the round ring frame the lenses 7 of the lamps will be convexed, enabling the reflectors 8 to disperse rays of light with substantial diverging lines of direction.

The bulbs 9 of the lamps may be wired direct or in series, and their conductors 10 are connected to binding posts 11 carried by brushes 12, which are in turn mounted in a suitable support 13. This support is carried by the round ring frame, and the brushes are extended downwardly and their extremities 110

operate upon circular conductor tracks 14, to which high tension conductor wires 15 are connected. These high tension conductor wires are employed for the purpose of carrying high tension current from any suitable source of current supply, not shown, which will furnish current to the high candle power lamps.

It is possible to so wire (but not shown)

- 10 the bulbs that the lamps of the upper half of the round ring frame may be shut off in any well known conventional manner not shown, that is should the device be used on aviation fields in order that after the aviator 15 locates the field due to the sphere of illumination, those around the field may operate the current so as to shut off the illumination of the upper half of the round ring frame.

Furthermore it is possible to construct the 20 frame 6 solid in the form of a band not shown and bolt or otherwise mount the lamps on the frame.

The invention having been set forth, what 25 is claimed is:

- 25 1. In an apparatus for broadcasting illumination, a supporting frame having a bed plate on its upper end, a shaft mounted vertically in said frame for revoluble movement therein, a round ring frame movable with 30 the upper end of the shaft, a plurality of high candle power search lamps arranged about the convexed surface of the round ring frame, whereby as the ring frame rotates with the shaft a truly spherical illumination may be 35 dispersed over a wide area, conductor tracks mounted on the bed plate of the first frame immediately under the ringed frame, a pair of yieldably mounted conductor brushes carried by the round ring frame and connected 40 direct or in series with the lamps and adapted to ride in contact with the conductor tracks, and means for furnishing high tension current to the lamps.

- 45 2. In an apparatus for broadcasting illumination, a frame of substantial height having a bed plate on its upper end, a pair of circular conductor tracks on the bed plate and provided with contact surfaces arcuate in cross section, and including binding terminals for high tension current, a shaft mounted vertically in said frame for revoluble movement therein, a round ring frame supported 50 on the upper end of the shaft and movable

therewith, a plurality of high candle power search lamps arranged about the convexed surface of the round ring frame, whereby as the shaft rotates a truly spherical illumination may be dispersed over a wide area above and below, a pair of yieldably mounted conductor brushes, having binding terminals operatively mounted on and carried by the round ring frame and connected direct or in series with the lamps, the construction and arrangement of the brushes being such as to engage with the arcuate surfaces of the 65 tracks, whereby current may be transmitted to the lamps, conductor wires connected with the binding terminals of the tracks adapted for transmitting high tension current to the tracks and the lamps through the medium 70 of the brushes.

3. In an apparatus for broadcasting illumination, a frame of substantial height having a bed plate on its upper end, a pair of circular conductor tracks on the bed plate and provided with contact surfaces arcuate in cross section, and including binding terminals for high tension current, a shaft mounted vertically in said frame for revoluble movement therein, a round ring frame supported on the upper end of the shaft and movable therewith, a plurality of high candle power search lamps arranged about the convexed surface of the round ring frame, whereby as the shaft rotates a truly spherical illumination may be dispersed over a wide area above and below, a pair of yieldably mounted conductor brushes, having binding terminals operatively mounted on and carried by the round ring frame and connected direct or in series with the lamps, the construction and arrangement of the brushes being such as to engage with the arcuate surfaces of the 75 tracks, whereby current may be transmitted to the lamps, conductor wires connected with the binding terminals of the tracks adapted for transmitting high tension current to the tracks and the lamps through the medium 80 of the brushes.

4. In an apparatus for broadcasting illumination, a frame of substantial height having a bed plate on its upper end, a pair of circular conductor tracks on the bed plate and provided with contact surfaces arcuate in cross section, and including binding terminals for high tension current, a shaft mounted vertically in said frame for revoluble movement therein, a round ring frame supported on the upper end of the shaft and movable therewith, a plurality of high candle power search lamps arranged about the convexed surface of the round ring frame, whereby as the shaft rotates a truly spherical illumination may be dispersed over a wide area above and below, a pair of yieldably mounted conductor brushes, having binding terminals operatively mounted on and carried by the round ring frame and connected direct or in series with the lamps, the construction and arrangement of the brushes being such as to engage with the arcuate surfaces of the 85 tracks, whereby current may be transmitted to the lamps, conductor wires connected with the binding terminals of the tracks adapted for transmitting high tension current to the tracks and the lamps through the medium 90 of the brushes.

5. In an apparatus for broadcasting illumination, a frame of substantial height having a bed plate on its upper end, a pair of circular conductor tracks on the bed plate and provided with contact surfaces arcuate in cross section, and including binding terminals for high tension current, a shaft mounted vertically in said frame for revoluble movement therein, a round ring frame supported on the upper end of the shaft and movable therewith, a plurality of high candle power search lamps arranged about the convexed surface of the round ring frame, whereby as the shaft rotates a truly spherical illumination may be dispersed over a wide area above and below, a pair of yieldably mounted conductor brushes, having binding terminals operatively mounted on and carried by the round ring frame and connected direct or in series with the lamps, the construction and arrangement of the brushes being such as to engage with the arcuate surfaces of the 95 tracks, whereby current may be transmitted to the lamps, conductor wires connected with the binding terminals of the tracks adapted for transmitting high tension current to the tracks and the lamps through the medium 100 of the brushes.

In testimony whereof he affixes his signature.

THOMAS J. BOWEN.
